UNITED STATES PATENT OFFICE

101,166

DESIGN FOR A CAN COVER

Albin L. Forsberg, Chicago, Ill., assignor to The Warfield Company, Chicago, Ill., a corporation of Illinois

Application May 18, 1936, Serial No. 62,713

Term of patent 14 years

To all whom it may concern:

Be it known that I, Albin L. Forsberg, a citizen of the United States, residing at Chicago, in the county of Cook and State of Illinois, have invented a new, original, and ornamental Design for a Can Cover, of which the following is a specification, reference being had to the accompanying drawing, forming a part thereof, in which:

Fig. 1 is a top plan view of a can cover showing my new design; and

Fig. 2 is a sectional view taken on line 2—2 of Fig. 1.

The design is characterized by being made of a single sheet of opaque material with its periphery beaded and its central area stepped up into a single plane, said central area being provided with two panels of unequal sizes each surrounded by a raised ridge and separated by a relatively wide flat cross bar.

I claim:

The ornamental design for a can cover, as shown and described.

ALBIN L. FORSBERG.
